APPARATUS FOR CARBURETED WATER GAS

Norman Henry Williams, Westminster, England,
assignor to Humphreys & Glasgow Limited,
Westminster, England

Application September 6, 1949, Serial No. 114,164
In Great Britain September 16, 1948

5 Claims. (Cl. 48—80)

1

Carbureted water gas apparatus usually comprises a generator, a carbureter and a superheater, the blast air passing through the generator and the blow gases down through the carbureter and up through the superheater and the uprun gas following the same course and being carbureted with oil admitted to the top of the carbureter and flowing therethrough in the same direction as the uprun gas.

When employing enriching oils such as gas oils which leaves no residue or only a slight residue on evaporation, the carbureter in which the oil is evaporated customarily contains checker-work. When using oils which leave an appreciable carbon residue on evaporation, it is desirable to use an empty carbureter having no checker-work.

With the object of obtaining better contact of gas with the walls of an "empty" or checkerless carbureter it is known to impart a spinning motion to the blast gases by passing them into the carbureter through a tangential inlet. It is also known to bring the gases from the generator to the carbureter through a downwardly sloping pipe entering the carbureter some distance above its base and tangential to its circumference but directed downwardly towards a section of the carbureter below the inlet. The gases then rise and pass through a throat above the gas inlet into the upper part of the carbureter into which oil is sprayed in a direction opposed to gas flow.

The present invention is primarily concerned with the carbureting of water gas, more particularly with heavy oil, in apparatus comprising a generator, carbureter and superheater, the disposition of which is or may be that of standard sets, and which apparatus is in consequence adapted to be readily formed from the generality of existing water gas sets by relatively minor reconstruction.

In apparatus according to the invention the carbureter is of the "empty" type and the gases from the generator flow downwardly through it to the bottom of the superheater and oil is injected into the lower part of the carbureter.

The connection from the generator enters the carbureter tangentially, or with a considerable tangential component, and is as close to the top of the carbureter as is constructionally convenient, in order to save height. In cases where the roof is of a cone or dome shape, the inlet connection may be taken into the cone or dome with the same object. It is unnecessary for the connection to enter the carbureter with an upward slope and undesirable for it to enter the car-

2

bureter downwardly and it is preferred that the connection be substantially horizontal. Beneath the inlet the carbureter is provided with an axial throat as close to the inlet as possible consistent with imparting the required spinning motion to the gases passing through the throat into the lower part of the carbureter.

The distance between the inlet and the throat is chosen to suit the inlet velocity of the gases and the diameter of the upper chamber, which may be less than, but is preferably not greater than that of the lower part of the carbureter into which oil is sprayed.

The throat may be formed by an annular inward projection of the carbureter walls, the upper surface sloping downwardly and inwardly towards the throat and the lower surface sloping outwardly and downwardly away from the throat and rejoining the side walls of the carbureter at an obtuse angle thus providing for the gases a passage, preferably short, with progressively decreasing diameter followed by one which progressively increasing diameter and avoiding the formation of relatively static pockets at the junction of the annular projection and the side walls.

It is essential that that portion of the carbureting vessel between the throat and the connection to the superheater, which portion constitutes the empty carbureter proper and into which the oil is sprayed, should be empty of checkers or other such obstructions tending to destroy the spinning motion of the gases.

During the uprun period of the cycle the make gases follow the same path through the apparatus as the blow gases, and oil is sprayed into them in that part of the carbureter which lies below the throat.

Oil may be sprayed into the carbureter either in the direction of gas flow or in opposition thereto, but in either case to minimise impingement on the walls, the spray should be delivered vertically and preferably symmetrically about the axis of the carbureter.

When the oil is sprayed in a direction counter to the flow of gas the oil spray and throat are so proportioned and situated relative to one another that the oil spray is contained in the space below the throat as indicated at 1' in Fig. 1.

The upper or inlet chamber together with the throat already described is a separate functional part of the apparatus which causes gases from the generator to move in a desired path through the carbureter proper and also prevents oil when sprayed in opposition to the gas flow from passing into the inlet chamber through the throat where

the gases have a relatively high velocity. It is apparent that this inlet chamber may be separate from the carburetor proper and connected thereto by a short pipe entering the top of the carburetor proper vertically and centrally and serving as the throat.

When using heavy oil, as much oil as is convenient may be added in the generator, where the carbon residues deposited from it are available for generation of gas.

Secondary air for combustion of the blow gases is preferably added at a point or points at which it will become thoroughly mixed with the gas before passing through the throat; such air may for example be added in the generator top, in the generator-carburetor connection or in the upper part of the inlet chamber. Excess air may also be admitted at one or more of these points for burning carbon deposits from the walls of the carburetor but it is preferred to admit air for combustion of carbon deposits on the walls at a level well below the top of the carburetor in such manner that it will mix preferentially with that part of the blow gases which is spinning or will spin round in contact with the carburetor wall and with any carbon deposits thereon, instead of passing down the central part of the carburetor without contacting and combusting such deposits. For example, carbon-burning air may be introduced peripherally at a point or points at the throat or where the gases are expanding after passing through the throat and other supplies may be added at a few points beyond. These additional air inlets may be tangential so that if air is supplied through them at a sufficiently high velocity it will tend to maintain or even increase the spinning of the blast gases. During the uprun no air will be added at these inlets. The admission of carbon-burning air peripherally to a spinning flow gas stream in a carburetor is the subject of my copending application No. 114,165.

The above described method of separate addition of air for burning of blow gases and for burning carbon deposits in the carburetor is preferred, but it is evident that by simultaneously adding air for both purposes, peripherally, at an intermediate location in the path of the gases through the inlet chamber, for instance at a suitable level in the vertical walls of the inlet chamber, an intermediate degree of mixing will result in the issuing gases, that is to say more air will remain in the peripheral gases than has penetrated to those issuing centrally. This is not as efficient as the preferred dual admission because that portion of the air intended for combustion of blow gases will not be uniformly mixed with these gases. The method may, however, conveniently be employed in certain cases in which it is not essential to obtain the most efficient operation.

In the accompanying drawings,

Fig. 1 is a diagrammatic elevation partly in section showing the generator, carburetor and superheater of a carbureted water gas set embodying the invention, the usual steam and air mains and connections being omitted for the sake of clearness, but are necessarily provided.

Fig. 2 is a horizontal section on the line 2—2 of Fig. 1.

Fig. 3 is a vertical section through the carburetor taken at the throat.

Fig. 4 is a horizontal section through the carburetor showing the inlets for additional air disposed below the throat and which are tangen-

tially disposed, same being a modification of those shown in Fig. 1.

Figs. 5, 6, 7, 8, 9 and 10 are diagrams illustrating methods of varying the rotational or spinning motion imparted to the gases entering the inlet chamber of the carburetor.

Referring more particularly to Figs. 1 and 2, *a* is the generator, *b* the carburetor and *c* the superheater. The generator *a*, the top of which 10 is connected to the top of the carburetor *b* by the pipe *d*, is shown equipped with a nozzle *e* (Fig. 1) for spraying oil onto the fuel bed thereof during the run, and with a number of air inlets *f* for marginally blasting with air during 15 the blow the upper part of the fuel bed to store heat in the upper part of the generator for vaporizing oil and to burn carbon residues deposited thereon from the oil.

The pipe *d* has a secondary air inlet at *g* and 20 enters the top part of the carburetor *b* tangentially. Below the level of this inlet pipe *d* the carburetor wall is formed with an annular inward projection *h* having sloped upper and lower surfaces. This projection *h* divides the carburetor vessel into an upper inlet chamber *b'* and a lower chamber *b²* which are connected by throat 25 *h'*. The chamber *b²* is connected by a pipe *j* with the superheater *c* and is provided with an oil spraying nozzle *i* which is shown directed upwards along the vertical axis of the vessel, but 30 may be located near the top of the chamber *b²* and be directed downwards as at *i'* in Fig. 1. The chamber *b²* between the throat *h'* and the pipe *j* between the carburetor and the superheater is 35 checkerless or "empty" and constitutes the carburetor proper. The pipe *j* is shown extending radially from the chamber *b²*, but it may extend tangentially therefrom.

The top of the superheater is connected by a 40 pipe *c'* to a washbox (not shown) and by a pipe *c²* to a waste heat boiler (not shown).

In Figs. 1 and 2 radial passages *k* are shown 45 extending from an annular channel *k'* through the under surface of the projection *h* for the introduction of carbon burning air to the periphery of the blow gas stream flowing into carburetor proper *b²*. *k²* is the air supply pipe to the channel *k'*.

In Figs. 3 and 4 the passages *k³* instead of 50 being radial are tangentially arranged so as to assist the spinning of the blast gases.

The rates of production of blow gases and uprun gases and hence the velocities with which 55 these gases pass through the connection *d* from the generator *a* to the carburetor *b* are however different and for a variety of reasons it is not practicable widely to alter their relative velocities by alteration of the relative durations of the blow and uprun periods. Moreover the degree of 60 rotation desired in the blow gases and run gases within the carburetor *b* is governed by quite differing requirements. During the blow period the object is to sweep the carburetor walls with hot gas to obtain the best transfer of heat from gas to wall and to burn off any deposited carbon. During the uprun period the degree of rotation is required to be adjusted in relation to the character of the oil spray so as to avoid flinging incompletely evaporated particles onto the wall by 65 centrifugal action, though it may be desired to cause the particles to pursue a rotating spiral path in the neighborhood of the hot brickwork.

It is therefore desirable in some cases to provide means of varying the rotational motion imparted to the gases in the inlet chamber *b'* during

either the blow phase or the uprun phase of the cycle or both either in the sense of augmenting or of reducing the rotation, or of increasing rotation during the one phase and reducing it during the other.

The rotation of gases in the inlet chamber b' may be increased by increasing their tangential velocity as they enter it, and suitable means for this purpose comprise a movable vane or vanes at or near the carbureter end of the inlet connection d deflecting the entering gases towards the wall while simultaneously imparting an increased velocity to the gases by constricting their entry path. Fig. 5 illustrates such an arrangement, l being a hinged vane which can be moved towards and from the wall of the pipe d opposite the vane hinge.

Reduced rotation of the gases in the inlet chamber b' may be brought about by a vane or vanes, preferably at the level of the inlet connection, which may be moved to impose an obstruction to the rotational motion of the gases but which can be moved out of their path. A vane l so arranged is illustrated in Fig. 6.

A plate sliding across the gas stream, say in a horizontal or vertical direction or other means may be used instead of a hinged vane. Figs. 7 and 8 illustrate arrangements corresponding to Figs. 5 and 6 of horizontally sliding plates l' .

As an alternative to varying the rotational movement by means of vanes or the like two gas inlets $d-d'$ to the inlet chamber b' may be provided, one of which d is the tangential inlet and the other d' , which may branch from the pipe d leading to the first inlet or may leave the generator at a separate point, does not enter the carbureter tangentially but enters it either centrally on the axis or radially, or in any other direction not imparting a rotating motion to the gases or imparting a reduced rotating motion or possibly even tending to destroy any rotating motion of gases entering through the tangential connection d . The proportions admitted through the two connections $d-d'$ may be varied as desired to give the appropriate rotational effect of the combined gases by means of valves, which may be of the butterfly type, in one or both connections, or by a directing vane at their junction. If desired, during the oiling period, the uprun gases may be passed through the carbureter b with very little or substantially no rotating motion. Fig. 9 illustrates diagrammatically such an arrangement having a branch d' from the tangential pipe d which branch is substantially radial to the chamber b' , l being a hinged directing vane at the junction of d' and d .

Fig. 10 shows a similar arrangement but the branch d' enters the top of the chamber b' axially, d and d' being provided with valves l to control the flow of gas therethrough. The valves are conveniently butterfly valves.

Because it is usually more important to minimise resistance to gas flow during the blow period than during the uprun period and because the rotational effect required during the blow period is usually greater than that required during the uprun period, it will generally be arranged that the rotational effect required during the blow period is obtained with no vanes then in the path of the gases and with all the gases entering through the tangential connection.

Water gas apparatus according to the present invention may include a generator provided with means whereby the coke or other fuel when

charged is subjected to heating by the process gases and may be also by radiation, for sufficient time to be thoroughly heated before oil is sprayed upon it. Also the carbureter may have a bosh or grate near the base and below its connection with the superheater filled with or supporting a bed of refractory material for retaining deposits from the carbureting oil spray and a second connection to the superheater and an air inlet below the bosh or grate.

I claim:

1. A carbureted water gas apparatus having a generator and having a carbureter devoid of checkerwork and having a superheater, said generator, carbureter and superheater being so connected by passages that the blast air passes through the generator and the blast gases pass down through the carbureter and up through the superheater, and the uprun follows the same course through the generator, down through the carbureter and up through the superheater; wherein the carbureter comprises a substantially cylindrical upper chamber having adjacent its top a substantially tangential gas inlet from the generator, said carbureter having a substantially cylindrical lower chamber of substantially same diameter as the upper chamber; a throat between the upper and lower chambers of the carbureter formed by an annular inward projection from the carbureter disposed a substantial distance below the gas inlet, the upper surface of which projection slopes downwardly and inwardly towards said throat, and the lower surface of which slopes downwardly and outwardly away from said throat; and movable means in said tangential carbureter inlet adjustable to divert the straight line flow of a portion of the gas in the connecting passage and to vary the angle of the lines of flow of said portion into said carbureter and the direction of said lines of flow in respect to the vertical axis of the carbureter.

2. In apparatus as set forth in claim 1, an air inlet in the carbureter below the level of the tangential gas inlet from the generator for admission of additional air to that part of the blast gas stream in the carbureter which is in contact with the wall of the carbureter.

3. In apparatus as set forth in claim 2, the additional air inlet in the carbureter being disposed tangentially of the wall of the carbureter.

4. In apparatus as set forth in claim 1, oil spraying means in the lower chamber of the carbureter below said throat.

5. In apparatus as set forth in claim 1, a second gas inlet branching from the tangential gas inlet from the generator for directing gases in a substantially radial direction into the carbureter upper chamber; and said means controlling the proportion of gas entering the upper chamber through said inlets.

NORMAN HENRY WILLIAMS.
